UNITED STATES PATENT OFFICE.

JOSEPH B. MURRAY AND THOMAS E. MURRAY, JR., OF BROOKLYN, NEW YORK.

HEAT-CONDUCTING TUBE.

Application filed June 17, 1924. Serial No. 720,512.

In certain prior applications, Nos. 642,427 filed May 31, 1923, and 642,725 filed June 1, 1923, there is described a certain hollow construction for walls and other parts of boilers or heaters and made up of tubes of rectangular, circular or irregular cross-section with fins or flanges extending lengthwise thereof so as to provide a heating surface exposed to the heating gases greater than the surface 10 which is in contact with the water or other fluid in the tube.

The present invention provides a unit and a method of producing the same from which such boiler walls and the like may be built. 15 The accompanying drawings illustrate embodiments of the invention.

Fig. 1 is a horizontal section of a side wall of a boiler built with the tubular units of the invention;

20 Fig. 2 is an enlarged perspective view of one of the tubes.

In another application pending concurrently herewith Serial No. 715,369, filed May 23, 1924, there is described a unit for the purpose 25 stated with flanges of certain shapes and methods of production and application. The present application is directed to a specifically different unit.

The boiler wall has on the inside a screen 30 composed of tubes 1 with lateral fins or flanges 2 overlapping each other. Outside of this screen is the usual wall made of refractory brick 3, tiles 4 of non-conducting material and an outer shell 5 of sheet metal.

35 As illustrated in Fig. 2 the flanges 2 are composed of a plate or flat bar extending continuously through the tube, so that the opposite flanges are integral with each other. The tube is made of semi-circular segments

with their edges brought to register at opposite sides of the flat plate and butt welded at the points of contact 6. The central portion 7 of the plate conducts the heat from the flanges 2 directly into the water or other fluid in the tube and thus provides a very efficient structure. The inner part 7 of the plate is provided with slots 8 at intervals so as to prevent circulation of the water on opposite sides of the plate.

As stated in application No. 715,369, above referred to, the tubes may be of various shapes and may be of ordinary low carbon steel, while the flanges may be made of special alloys or specially coated to resist oxidation.

While we have described with great particularity of detail certain embodiments of our invention, yet it is not to be understood therefrom that the invention is restricted to the particular embodiments disclosed. Various modifications may be made by those skilled in the art without departure from the invention as defined in the following claim.

What we claim is:

A heat conducting unit comprising a tubular member made up of a plate and of hollow segments welded to opposite sides of said plate to provide a tube with lateral flanges extending beyond the tube and exposed to the surrounding medium, the part of the plate within the tube being apertured to permit circulation between opposite sides thereof.

In witness whereof, we have hereunto signed our names.

JOSEPH B. MURRAY.
THOMAS E. MURRAY, JR.
